Watson, Coit, Moore & Grindell,
ATLANTA.

UNITED STATES PATENT OFFICE.

THOMAS EDWARD RUDDERHAM, OF SUDSBURY, ENGLAND.

FOUNTAIN PEN.

Application filed January 29, 1923. Serial No. 615,676.

To all whom it may concern:

Be it known that I, THOMAS EDWARD RUDDERHAM, a subject of the King of England, residing at Sudbury, Suffolk, England, have invented certain new and useful Improvements in Fountain Pens, of which the following is a specification.

This invention is for improvements in or relating to fountain pens and has for its object to provide such a pen with a cap of improved construction such that the writing-nib can be exposed for use without removing the cap.

It has heretofore been proposed to provide a fountain pen with a longitudinally split, spring-controlled cap arranged to open and close when slid longitudinally on the end of the pen and to allow the nib to protrude when the cap was slid back on the pen. It has also been proposed to provide a fountain pen whereof the body portion or reservoir had a cylindrical end part into which the nib could be retracted, a sleeve having a closure member on one end being mounted to rotate on, but not to slide lengthwise of, the body portion, the arrangement being such that when the nib was retracted the sleeve could be rotated to cause the closure member to close and open the said end part of the body portion.

According to this invention there is provided in a fountain pen, the combination with the body portion or reservoir of the pen, of a cap mounted to slide lengthwise on one end of the body portion and having in its free end a hole to permit the projection therethrough of the writing-nib when the cap is slid back on the pen and means operative with the sliding movement of the cap for covering the said hole when the cap is advanced.

Preferably, the cap comprises an outer and an inner shell rotatable relatively to one another, both slidable endwise on the pen and both having in their ends an orifice to permit the writing-nib to project therethrough, and means operatively connected with the pen which is such that one shell must rotate relatively to the other as the cap is moved in one direction or the other.

In the accompanying drawings, which il-

lustrate one method of carrying out this invention:

Figure 1 is a longitudinal section through the cap-end of the pen with the cap in the position for covering the writing-nib.

Figure 2 is a longitudinal section through the cap-end of the pen with the cap in the position for exposing the writing-nib, and

Figure 3 is an external view of the inner shell of the cap.

Like reference letters indicate like parts throughout the drawings.

The pen A may be of any convenient construction, but the writing-nib A¹ is carried eccentrically at the end instead of being situated in the usual central position.

Sliding over the end of the pen is a cap comprising two shells B and C respectively. The shell B has in it a cam-slot B¹ which is spiral at that end furthest from the closed end of the cap and straight at that portion which is near the closed end. A pin D is fixed in the pen body and engages this cam-slot B¹, and the spiral portion is arranged to cause the shell to rotate through 180° by reason of engagement with the pin D when the shell is moved endwise.

In the inner face of the shell C is a straight longitudinal channel C¹ and the pin D projects through the cam-slot in the shell B into this channel C¹.

The covering-ends of the two shells each have in them a hole B² and C² respectively which are large enough to permit the writing-nib A¹ to project through. The hole C² is opposite the writing-nib, but the hole B² is out of register with the hole C² when the parts are in the covering position shown in Figure 1.

A collar E is screwed into the end of the outer shell C to hold this normally upon the pen.

It will be seen that with the composite cap arranged as described above endwise movement of the cap in the direction to uncover the nib will cause the inner shell B to rotate so that the two holes B², C² are in register by the time the end of the cap reaches the point occupied by the writing-nib. The two shells then continue to

slide without relative rotation so that the nib can be made to project as shown in Figure 2. A reverse movement effects the covering of the nib and the bringing of the 5 holes B²; C² again out of register.

The parts are easily assembled or separated for examination or repair as the collar E, in conjunction with the pin D are the only parts which hold the cap on 10 the pen. By removing the collar E the shell C can be removed and then by removing the pin D, which conveniently takes the form of a grub-screw, the shell B can be removed.

15 Obviously, the details of the invention can be varied without departing from the spirit of the invention, and the particular construction described is only set forth by way of example and not by way of limitation.

20 What I claim as my invention and desire to secure by Letters Patent is:

1. In a fountain pen, the combination with the body portion of the pen, and a 25 writing nib carried at one end thereof, of a cap for the nib comprising two parts whereof one is rotatable relatively to the other about the longitudinal axis of the pen, which cap is slidable endwise on said body portion and 30 has in one of said parts an orifice to permit the nib to project through it when the cap is at the limit of its movement in one direction, the other of said parts constituting a closure member for said orifice, and 35 means operative with the sliding movement of the cap and arranged to rotate one of said parts in relation to the other to close and open the orifice when the cap is moved endwise in either direction on said body portion, substantially as described.

2. In a fountain pen, the combination with the body portion of the pen, and a writing-nib carried eccentrically at one end thereof, of a cap for the nib comprising an 45 outer shell and an inner shell rotatable relatively to one another, which cap is slidable endwise at one end on the said body portion and both said shells have in their other end an eccentric orifice to permit the nib 50 to project therethrough when the cap is at the limit of its movement in one direction, and means operatively connecting said cap with said body portion, which means is adapted to rotate one shell in relation to 55 the other to close and open the orifices when the cap is moved endwise in either direction on said body portion, substantially as described.

3. In a fountain-pen, the combination 60 with the body portion of the pen, and a writing nib carried eccentrically at one end thereof, of a cap for the nib comprising an outer shell guided to move endwise without rotation on said body portion, and an 65 inner shell rotatable relatively to the outer

shell and slidable endwise on the body portion, which shells have in their end remote from the body portion each an eccentric orifice to permit the nib to project therethrough when the cap is at the limit of its 70 movement in one direction, and means operatively connecting said cap with said body portion, which means are adapted to rotate the inner shell in relation to the outer to close the orifices as the inner shell moves 75 endwise during at least part of such endwise movement in the other direction, substantially as described.

4. In a fountain pen, the combination with the body portion of the pen, and a 80 writing-nib carried eccentrically at one end thereof, of a cap for the nib comprising an outer shell non-rotatable on but slidable endwise on the nib end of the body portion, and an inner shell rotatable in the outer shell 85 and slidable endwise on said body portion, which shells have in their ends directed away from the body portion each an eccentric orifice, and a pin mounted on the said body portion, said inner shell having a 90 longitudinally disposed cam-slot into which said pin extends, said slot being so shaped as to bring the orifice in the one shell into register with the orifice in the other at the limit of the movement of the cap in the 95 one direction and out of register at the limit of the movement of the cap in the other direction, substantially as described.

5. In a fountain pen, the combination with the body portion of the pen, and a 100 writing-nib carried eccentrically at one end thereof, of a cap for the nib comprising an outer shell non-rotatable on but slidable endwise on the nib end of the body portion, and an inner shell rotatable in the outer 105 shell and slidable endwise on said body portion, which shells have in their ends directed away from the body portion each an eccentric orifice, said inner shell having a longitudinally disposed cam-slot and said outer shell having a straight longitudinal 110 guideway, and a pin mounted on the said body portion and extending through said slot into engagement with said guideway, said slot being so shaped as to bring the 115 orifice in the one shell into register with the orifice in the other at the limit of the movement of the cap in the direction towards the body portion and out of register at the limit of the movement of the cap in the other 120 direction, substantially as described.

6. In a fountain pen, the combination with the body portion of the pen, and a writing-nib carried eccentrically at one end thereof, of a cap for the nib comprising an 125 outer shell non-rotatable on but slidable endwise on the nib end of the body portion, and an inner shell rotatable in the outer shell and slidable endwise on said body portion, which shells have in their ends 130

directed away from the body portion each
an eccentric orifice, said inner shell having a
longitudinally disposed cam-slot, and said
outer shell having in its inner face a straight
5 longitudinal channel, and a pin mounted on
said body portion and extending through
said slot into said channel, said slot being
so shaped as to bring the orifice in the one
shell into register with the orifice in the
other at the limit of the movement of the 10
cap in the direction towards the body por-
tion and out of register at the limit of the
movement of the cap in the other direction,
substantially as described.

In testimony whereof I affix my signature.

THOMAS EDWARD BUDDERHAM.
